UNITED STATES PATENT OFFICE.

JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK.

GARMENT PRESS.

Application filed September 19, 1925. Serial No. 57,264.

This invention relates to garment presses and to operating mechanism therefor, and more particularly relates to improved balancing means for the movable press jaws or for the press head.

In garment pressing machines now largely in use, it is the custom of press manufacturers to mount the pressing head on one end of a long horizontal press lever. This press lever rocks in a vertical plane on a horizontal fulcrum axis to raise and lower a press head and this lever projects rather far back from the press frame and causes the press to really occupy more floor space than would seem necessary with an otherwise compact frame.

In order to balance the rather heavy head, it is necessary to mount a heavy weight on the other end of the press lever. This further increases the size of the machine and space consumed, and furthermore the weight must be heavy if the head is to be balanced on a relatively short rear end lever arm. It is not practical to increase the length of the lever arm to correspondingly decrease the balancing weight for that would render the machine still more cumbersome and unsightly and require still more floor space.

According to my invention, it is not necessary to project the rear end of the lever to the rear of the press frame and thus be in the way but my invention permits the press to be placed close to the wall or close to another pressing machine and thus save floor space.

In this improved press the rearwardly projecting, unsightly, large, heavy weight carrying, short integral lever arm is simply reversed in all these respects. It is made in two pieces geared together and the weight carrying section of the press lever is placed under the table of the press and carries a light weight, not a heavy one, because the balancing arm is longer and possesses increased leverage. It is out of the way under the press table. It projects inside the machine instead of to the rear.

The accompanying drawing illustrates in partially diagrammatic form the invention as adapted to a pressing machine. The press jaws are shown in closed and pressing position with the pedal down and the operating means locked to maintain the jaws closed.

Referring further to the drawing for a more detailed description of the invention,

there is shown a press frame 10 on which a press table 11 is mounted together with a back board 12 to prevent the garment or other work being pressed from falling to the rear of the press. Press jaws are mounted on the press frame and comprise the usual form of stationary buck 13 and movable head 14. The jaws or press head and buck open wide to admit the work. A jaw carrying press arm 15 is fixed to the head 14 at one end and is pivoted at 16 on the frame at the other end thereof. The press head arm 15 is preferably composed of a horizontal portion 16 and substantially vertical portion 17 and the head 14 is lifted high above the buck 13 by swinging this arm. The lower end of the arm is made integrally with a gear 18 forming part of the press operating mechanism.

A balancing arm 20 is mounted under the press table 11 with its forward end projecting towards the front of the machine and its rear end pivoted at 21 on the frame 10. The rear end of the balancing arm 20 is made with a gear 22 which engages the gear 18. The balancing arm 20 is normally disposed in a horizontal plane when the press is closed as shown in the drawing and the front end swings up and down, moving in a direction opposite to that of the head 14. In other words the arms 20 and 15 are geared together which imparts an opposite direction of travel, for it is to be noted that as the press head arm 15 lifts upwardly the balancing arm 20 moves downwardly. A balancing weight 23 is adjustably mounted on the horizontal balancing arm 20 and preferably placed toward the forward end thereof so as to obtain as much leverage as possible through the gears 18 and 22 in order to lift the head 13 or in order to balance it as the case may be.

One balancing arm 20 and weight 23 are shown mounted on the outside of the press frame out of the way under the table 11 but it is to be understood that a double set of these parts may be employed, one to each side of the press if desired. In some forms of pressing machines where the steam piping and other equipment is carefully arranged to give clearance within the frame it is possible to place one arm and weight inside of the leg frames but in case of pressing machines so filled with piping and other equipment within the frame, then the parts

may be readily placed outside the frame 10 but directly underneath the overhanging table ends and thus be kept out of the way and not interfere with any other parts of 5 the pressing machine.

The weight or weights 23 are relatively light, not heavy, because they work through a long leverage and the gear ratio of the gears 18 and 22 may if desired be so designed 10 as to further increase the leverage so as to further decrease the weight 23.

A handle 25 is mounted on the head 14 to facilitate drawing the head down manually by the operator as is usual in pressing machines. An additional feature as regards 15 manually operating the press may be incorporated in this machine if desired and to this end another handle 26 is made on the front end of the balancing lever 20. This 20 handle 26 comes to rest in its uppermost limited position when the press is closed, coming to rest at a point adjacent the front edge of the table 11 which is convenient and easy for the operator to reach without stooping 25 down. While it is true that the handle 26 travels rather far down towards the floor on which the machine is placed as the head lifts, it is also true that the operator does not use the handle 26 until the head 14 has 30 practically reached contact with the buck 13 whereupon any additional power needed to close and lock the press may be readily obtained by the operator taking hold of the handle 26 and lifting upwardly thereon to 35 facilitate tightening the press jaws together as will be more fully understood after the foot pedal operating means is described.

Any suitable operating means may be used 40 to open and close the press, that is to raise the head 14 high above the buck and close it down thereupon against the work. Motor means may be used to advantage with the improved balancing means, but in this case I have illustrated a foot operated locking 45 toggle to actuate the head 14. To this end a pedal 28 is pivoted at 29 on the frame 10 with an integral upstanding toggle arm 30 pivotally connected at 31 to a short toggle link 32 the upper end of which is pivoted at 50 33 to the balancing lever 20. A hand adjusting wheel 34 constitutes a shortening and lengthening device which is incorporated in one of the toggle links and is used to finely 55 adjust the distance between the toggle pivot points or pins 29 and 33 in order that the toggle point 31 may be forced past a straight line connecting the points 29 and 33 thereby causing the toggle 30-32 to reach an overstraightened locked position as shown 60 in the drawing; thus holding the head 14 under tight compression on the buck 13. The handle 26 if lifted slightly by the operator as he depresses the pedal 28 aids greatly in bringing the toggle 30-32 to overstraightened locked position.

A kick-off pedal 36 is pivoted at 37 on the frame and is adapted to be thrust upwardly against the pedal 28 by the operator. The kick-off pedal 36 causes the toggle 30- 70 32 to be broken to force the toggle pin 31 to swing counterclockwise to broken position which permits the weight 23 to act downwardly to open the press thereby bringing all parts into an open position as along the dotted line. 75

In the operation of the press, the work is spread upon the buck 13 and the head 14 is drawn down thereupon either by depressing the pedal 28 or by pulling down the handle 25 or by using both such means and, in addition thereto, for finally locking the press, by pulling upwardly on the handle 26 if desired to thus facilitate the operation of the machine. The handle 26 stands in a convenient position to the operator and is particularly 80 useful in edge pressing machines and other high powered pressing machines which are worked by operators. In other words some presses are required to produce high compression and yet be worked by operators and 85 in such cases, it materially aids the operator in finally overcoming the resistance of the toggle pivot pin 31 forcing it to move to overstraightened locked position if the operator will lift up on the handle 26 at the end 90 of the closing action. It is to be noted that when the pedal 28 is going down, the handle 26 on the balancing arm is going up. This arrangement permits the operator to better utilize his physical power with less exertion 95 by simultaneously pressing his foot and lifting up by hand. This is a more natural way to exert man power than by attempting to do all the work with the foot only. By lifting up on the handle 26 the operator works 100 through the gears 18 and 22 to aid in throwing the toggle over to a locked position and thereby does not have to jump up and down on the pedal 28 to lock the toggle. By a simple operation of simultaneously pressing 105 his foot and lifting his hand the operator more easily and with less exertion closes the press into locked position. 110

Many foot power pressing machines 115 worked by operators are not required to be locked at all because of the fact that tailor work or steam valet pressing of clothes requires only a light patting or stroking action of the head on the garment and in such case this pressing machine has its toggle 24 set to 120 such an adjustment that it will not lock and so the operator readily causes the head 14 to pat or stroke lightly the work on the buck 13 and in that case it is not necessary to use the handle 26. 125

While this invention is explained in connection with foot and hand operated presses, it is to be understood that the balancing mechanism is readily adapted to motor driven presses because the improved balance- 130

ing means is placed under the table out of the way whether for foot operated press or power driven machines.

This improvement provides a press operating means or mechanism of suitable kind including the gear transmission 18-22 by which press opening and closing motion is imparted to the movable press jaw, and by which compression is obtained between the jaws. The press operating means is simple in construction and readily lends itself to the inclusion of balancing means such as the weight 23 which also works through the gear transmission.

15 What I claim is:

1. A press comprising, cooperating press jaws, one of them being movable, a pivotal arm carrying the movable press jaw, another pivotal arm, a weight carried with the second arm to balance the movable press jaw, means operatively connecting together the two pivotal arms, and a pedal disposed beneath the second arm and connected thereto to work the press.

25 2. A press comprising in combination, cooperating press jaws, a pivotal arm carrying a movable press jaw, another pivotal arm, a weight mounted on the second arm to balance the movable press jaw, gears interposed between the two arms operatively connecting them together, and means to actuate the arms to open and close the press.

35 3. A press comprising in combination, cooperating press jaws, a pivotal arm carrying a movable press jaw, another pivotal arm, a weight mounted on the second arm to balance the movable press jaw, a gear integrally formed on each pivotal arm and meshing together to cause the arms to swing in opposite directions, and means to actuate the arms to open and close the press.

40 4. A press comprising in combination, cooperating press jaws, a pivotal arm carrying a movable press jaw, another pivotal arm, a weight mounted on the second arm to balance the movable press jaw, means operatively connecting together the two pivotal arms, means to actuate the arms to open and close the press, and a handle carried by each arm which handles travel in opposite directions and adapted to be manually operated if desired by the operator to facilitate the operation of the aforesaid means.

45 5. A press comprising in combination, cooperating press jaws, a pivotal arm carrying a movable press jaw, another pivotal arm, a weight mounted on the second arm to balance the movable press jaw, means operatively connecting together the two pivotal arms, means to actuate the arms to open and close the press, and a handle carried on the second arm upon which the operator may manually work in conjunction with the means to open or close the press.

60 6. A press comprising in combination, co-

operating press jaws, a pivotal arm carrying a movable press jaw, another pivotal arm, a weight mounted on the second arm to balance the movable press jaw, means operatively connecting together the two pivotal 70 arms, a pedal connected with the aforesaid pivotal arms by which the press is closed by the operator's foot, and a handle carried by the second arm adapted to be manually operated if desired. 75

7. A press comprising in combination, a frame, cooperating press jaws comprising a head and buck, a table disposed under the buck supported on the frame, an arm having its rear end pivotally mounted on the frame 80 and reaching horizontally forwardly across the table with its front end fixed to the head, a balancing arm horizontally disposed under the table with its rear end pivoted on the frame, means operatively connecting the two arms together, a balancing weight mounted on the front end of the last named arm, and a handle carried on the forward end of the arm under the table convenient to the operator. 90

8. A press comprising in combination, a frame, cooperating press jaws comprising a head and buck, a table disposed under the buck supported on the frame, an arm having its rear end pivotally mounted on the frame 95 and reaching horizontally forward across the table with its front end fixed to the head, a balancing arm horizontally disposed under the table with its rear end pivoted on the frame, means operatively connecting the two arms together, a balancing weight mounted on the front end of the last named arm, a handle carried on the forward end of the arm under the table convenient to the operator, and foot operated mechanism connected 100 with the balancing arm to aid in operating the press. 105

9. A press comprising in combination, a frame, cooperating press jaws mounted thereon consisting of a movable head and stationary buck, a handle carried on the head, a swing arm attached at one end to the head and pivoted at other end on frame, an arm pivoted in the frame, gears connecting the arms together causing them to move 110 in opposite directions, and a handle fixed on the outer end of the last arm and adapted to swing downwardly as the first named handle swings upwardly. 115

10. A press comprising in combination, a frame, cooperating press jaws mounted thereon consisting of a movable head and stationary buck, a handle carried on the head, a swing arm attached at one end to the head and pivoted at other end on frame, an arm pivoted in the frame, gears connecting the arms together causing them to move in opposite directions, a handle fixed on the outer end of the arm and adapted to swing downwardly as the first named handle swings 120 125 130

upwardly, locking means cooperating with one of the arms to lock the head closed, and a weight mounted on the arm adjacent the handle to balance the head.

tached to the frame and its upper end connected with the last named arm and constituting a locking toggle, and a pedal integral with the lower toggle link. 35

- 5 11. A press comprising in combination, a frame, cooperating press jaws mounted thereon consisting of a movable head and stationary buck, a handle carried on the head, a swing arm attached at one end to the head 10 and pivoted at other end on frame, an arm pivoted in the frame, gears connecting the arms together causing them to move in opposite directions, a balancing weight cooperating with the gears to counterbalance 15 the head, a toggle having one end pivotally connecting with one of the arms and the other end pivotally attached to the frame, a pedal integrally formed with one of the toggle links, and a handle carried by the 20 last named arm to aid in manually locking the toggle as the pedal is depressed.

12. A press comprising in combination, a frame, cooperating press jaws mounted thereon consisting of a movable head and 25 stationary buck, a handle carried on the head, a swing arm attached at one end to the head and pivoted at other end on frame, an arm pivoted in the frame, means operatively connecting together the arms, a balancing 30 weight cooperating with the aforesaid means to counterbalance the head, a toggle standing vertically with its lower end pivotally at-

13. A press comprising, cooperating press jaws, a member connected with one of said jaws and movable to close said jaw on the other, a gear formed on said member, a 40 second gear meshing with said first gear, means secured to said second gear tending to rotate said gear in one direction to separate the jaws, and means for overcoming said rotating means to rotate said second gear in 45 the opposite direction to cause compression between the jaws.

14. A press comprising, cooperating press jaws, a member connected with one of said jaws and movable to close said jaw on the 50 other, a gear formed on said member, a second gear meshing with said first gear, a weight connected to and movable with said second gear, and means for rotating said second gear. 55

15. A press comprising, cooperating press jaws, a lever supporting one of said press jaws, a gear formed on one arm of the lever, a second gear meshing with said first gear, a weight connected to and movable with said 60 second gear, and means for rotating said second gear.

In testimony whereof I affix my signature.
JAMES CAMROD LEDBETTER.
